(57) **CLAIM**

The ornamental design for a gun sight accessory mount, as shown and described.

DESCRIPTION

FIG. 1 is a perspective view of a gun sight accessory mount; FIG. 2 is a front side view thereof, the rear side being a mirror image;

FIG. 3 is a right view thereof;

FIG. 4 is a left view thereof;

FIG. 5 is a top view thereof;

FIG. 6 is a bottom view thereof; and,

FIG. 7 is a front view thereof, showing a fastener secured to the gun sight accessory mount.

The broken line showing fastener is included for the purpose of illustrating environmental structure and forms no part of the claimed design.
